SWITCH-POINT-LOCKING DEVICE

Application filed July 25, 1928. Serial No. 295,201.

Our present invention has reference to a safety switch point locking device, our object being the provision of simple, cheaply constructed but thoroughly efficient means for locking the switch point close to the main rail, except when the train crew is using the switch.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Figure 1 is a plan view of our improvement.

Figure 2 is a side elevation thereof, with parts broken away and the rails or switch points being in section.

Figure 3 is an enlarged detail elevation, with parts in section, to better illustrate the locking plate and its engagement with the slide bar.

Figure 4 is a transverse sectional view approximately on the line 4-4 of Figure 3.

Figure 5 is a detail sectional view approximately on the line 5-5 of Figure 1.

Figure 6 is a plan view of the latching plate but showing the same provided with an extension as when employed on the opposite sides of the rails to those disclosed by the drawings.

Referring now to the drawings in detail, the numerals 1-1 designate respectively the main rails and the siding rails of a railway system, 2 the slideable switch points, 3 the ties upon which the main and siding rails are spiked and 4 the head block. On the top of the head block we bolt the upper plates 5 of guides 6, 7 and 8, respectively. By reference to the drawings it will be seen that the rectangular or channel portions of the guides 50 extend along the same side of the head block,

and that the guide 7 is disposed a slight distance inward of the guide 8, but these guides 7 and 8 have their confronting faces contacting. The guides 6 and 8 receive therethrough a slide bar 9, while pivoted, as at 10, in the guide 7 there is the end 11 of our improved locking plate 12. The offset end of the locking plate 12 may be offset in opposite directions with respect to the longitudinal plane of the said plate, in accordance with the side of the head block on which the plate is arranged, the said end 11 being offset in order that the body of the locking plate may be in snug engagement with one of the sides of the slide bar 9. The locking plate 12, on its upper edge is formed with a depression 13, one of the end walls provided by the said depression, that next to the end 11, being formed with a hook extension 14 which, as disclosed by Figure 3 of the drawings, overlies the inner base flange of one of the main rails. The second wall provided by the notch 13 is indicated by the numeral 15 and is straight. This wall 15 is designed to engage with the outer base flange of the switch rail for holding the switch rail against the main rail when the slide bar 9 has been actuated in a manner which will presently be described.

The slide is formed on its upper edge with a substantially V-shaped projection 16 and in a line with the inner wall of this projection the said bar is formed with an angle slot 17. This slot receives therethrough a bolt or pivot 18 that passes transversely through the locking bar 12, outward of the shoulder 15 thereof. When the device is employed on the second side of the track to that disclosed by the drawings, the locking bar is extended a suitable distance beyond its shoulder 15 and is provided with an opening 19 for a pivot similar to the pivot 18.

The slide bar 9 has its outer end connected to the crank portion 20 of a shaft 21. This shaft is journaled through suitable bearing openings in the base portion 22 of a two-part stand. The confronting edges of the sections of the stand are spaced from each other and are held so spaced by means 23. Secured to the shaft 21 and received between 100

the segmental side plates of the stand sections 22 there is the throw lever 24 for the slide bar 9. This throw lever is, of course, fixedly secured to the shaft 21. By reference to the drawings it will be seen that the upper and lower walls provided by the segmental sides of the stand 22 are formed with spaced pairs of substantially rectangular notches 25—25 and 26—26, respectively. These notches are designed to receive therein blocks 27 and 28, respectively, which are guided through the widened and slotted end of the throw lever 24 and which blocks are secured to a rod 29 that has an operating handle 30 which is pivotally secured to the throw lever 24.

The rod 29 is influenced by a spring 31 so that its blocks 28 are normally held in either of the series of notches in the stand. By this arrangement it will be noted that when the throw lever is in its vertical position and the locking plate is in its inactive position as disclosed by Figure 3 of the drawings, the throw lever cannot be accidentally actuated.

The throw lever and its stand 22 are located in close proximity to the switch stand 32. The switch stand is provided with the usual turnable rod 33 that carries the semaphore 34, the lower end of the said rod being cranked and pivotally connected to the throw rod 35 for the connecting or bridle bar 36 that carries the clamps 37 that are bolted to the confronting faces of the switch points 2.

The semaphore rod has secured thereto the usual outstanding arm 38 to which is pivoted the switch operating lever 39, the said lever designed to be received in spaced notches in the head 40 of the switch stand, and to be locked in these notches in the usual manner. In the present instance there is attached to the throw lever 24 and to the locking means for the throw arm of the switch lever a strong element such as a flexible chain 41. As the throw lever 24 must be swung outwardly with respect to the switch stand 32 it will be noted that this cannot be accomplished as long as the throw arm for the switch is locked.

The locking means, of course, may be readily released so that the switch may be operated in the usual manner from the switch stand, but when the lever 24 is swung to bring its latching blocks into the lower notches on the stand 22 a longitudinal movement will be imparted to the slide bar 9 which causes the locking plate 12 to have its pivot 18 ride in the upwardly disposed angle slots 17 and thereby elevate this end of the locking plate to bring its shoulder into locking engagement with the outer edge of the base flange of the switch rail and to effectively lock the switch rail against the main rail.

Having described the invention, we claim:

1. In combination with a railway switch, means for locking the switch point to the main rail, comprising a plate having an offset end which is pivotally supported, and

which has its top edge notched, one of the end walls provided by the notch having a hooked extension to overlie the outer base flange of the main rail, a slide bar, guides therefor, said slide bar being arranged against the plate and having an angle notch therethrough, a pin passing through the plate and received in the notch, a crank shaft to which the slide bar is connected, a throw lever for the crank shaft and means for locking the throw lever when swung to move the slide bar to swing the locking plate to bring the base flanges of the rails into and in contacting engagement with the walls of the notch, or when swung to lower the plate to permit of the movement of the switch rail.

2. In combination with a railway switch, and operating means therefor including a switch stand carrying a semaphore arm, a throw arm pivotally associated with the semaphore arm and received in notches in the switch stand, of a locking means for holding the switch rail against the main rail, comprising spaced guides, a plate having an offset end pivotally secured in one of said guides, said plate having its upper edge notched and one wall of the notch being formed with a hooked extension to overlie the outer base flange of the main rail, a slide bar movable through the remaining guides, said slide bar having an angle upwardly directed notch therethrough, a bolt member passing through the locking plate and received through said opening, a two-part stand disposed opposite the switch stand, a shaft journaled through the stand and having a cranked end to which the slide bar is connected, said stand including spaced segmental plates having upper and lower pairs of alining notches therethrough, blocks spring influenced into said notches, and said blocks being guided through the lower portion of the throw lever, a rod connected with the blocks, a hand operating lever for the rod pivotally secured to the throw lever and a chain secured to the handle portion of the throw lever and designed to be connected with the locking means for the throw arm of the switch stand.

In testimony whereof we affix our signatures.

EMIL W. MAVES.
WALTER B. MEWS.
